Primary Examiner — Michael A Maharajh

(57) **CLAIM**

The ornamental design for a facial massager, as shown and described.

DESCRIPTION

FIG. 1 is a front, right and top perspective view of a facial massager showing our new design;

FIG. 2 is a rear, left and bottom perspective view thereof;

FIG. 3 is a front, right and top perspective view of a handle of the facial massager with a first head;

FIG. 4 is a front, right and top perspective view of the handle of the facial massager with a second head;

FIG. 5 is a front, right and top perspective view of the handle of the facial massager with a third head;

FIG. 6 is a front view thereof;

FIG. 7 is a rear view thereof;

FIG. 8 is a left side view thereof;

FIG. 9 is a right side view thereof;

FIG. 10 is a top plan view thereof; and,

FIG. 11 is a bottom plan view thereof.

The broken lines in FIGS. 3-5 showing the handle of the facial massager depict environment only and form no part of the claimed design. The other broken lines in the drawings depict portions of the facial massager that form no part of the claimed design.

1 Claim, 11 Drawing Sheets
